WITHDRAWING MEANS FOR SIDE SLIP WEFT DETECTORS

Filed May 25. 1926

2 Sheets- Sheet 1

A technical drawing of a cylinder assembly. It features a central vertical cylinder with a piston rod extending from the top. The rod is labeled with a large letter 'P' at its top end. A horizontal rod, labeled '62 61' in a stylized font, is attached to the side of the cylinder. The entire assembly is set against a background with a hatched pattern.

UNITED STATES PATENT OFFICE.

HAROLD L. BLANCHARD, OF MILLBURY, MASSACHUSETTS, ASSIGNOR TO CROMPTON & KNOWLES LOOM WORKS, OF WORCESTER, MASSACHUSETTS, A CORPORATION OF MASSACHUSETTS.

WITHDRAWING MEANS FOR SIDE-SLIP WEFT DETECTORS.

Application filed May 25, 1926. Serial No. 111,661.

This invention relates to means for withdrawing loom weft detectors of the side slip type and it is the general object of the invention to improve upon means heretofore used for accomplishing this result by a very simple and inexpensive mechanism.

Weft detectors for multi-color automatic looms are usually located on the magazine end of the loom and where they are of the type which enter a side wall of the shuttle provision must be made for withdrawing the detector on transferring beats of the loom in order to provide a clear path for the incoming full bobbin. This movement of the detector out of the path of the bobbin must also be accomplished without giving a second indication to the magazine and it is a further object of my invention to accomplish these two results by a minimum of parts which shall be under control of the transfer mechanism.

In the usual form of multi-color weft replenishing mechanism indication of weft exhaustion is communicated to the magazine by means of a floating or actuator lever which normally has a downward movement on detecting beats of the loom, this movement being interrupted by a so-called controller on indicating beats. It is a further object of my invention to combine the controller for the actuator lever and the withdrawing device for the detector in one part so placed as to be under control of the transfer mechanism.

A more specific object of my invention is to provide a connection for withdrawing the detector by a device having somewhere in its length a surplus amount of material which can be used to afford adjustments.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a top plan view of a detector embodying my invention, the shuttle and bobbin being indicated in dotted lines and portions of the mechanism being indicated in section,

Fig. 2 is a vertical section on line 2—2 of Fig. 1,

Fig. 3 is a front elevation on a reduced scale of the structure shown in Fig. 1,

Fig. 4 is a perspective view of the withdrawing means,

Fig. 5 is a section on line 5—5 of Fig. 1, and

Fig. 6 is a fragmentary view of the forward portion of the withdrawing device after the loop therein has been contracted to afford a separating adjustment of the two legs of the device.

Referring particularly to Figs. 1, 2, and 3 it will be seen that I have provided a loomside 10 and breast beam 11 on which is mounted the frame 12 of a weft replenishing mechanism preferably of the multi-color type such as set forth in Patent No. 1,030,748. The frame 12 is provided with a stud 13 on which is pivotally mounted the hub 14 of a transerrer lever 15 the rear bobbin engaging arm 16 of which extends over the shuttle S and bobbin B when the lay is on front center. The transerrer arm has depending legs 17 between which extends a stud 18 by means of which the transerrer is given a downward movement on the transferring pick of the loom by connections not shown.

A stand 19 is bolted to the loom frame and has vertically reciprocably mounted therein a block 20 on which is pivoted an actuator lever 21 the inner end of which is connected to a magazine actuating rod 22 and the other end of which lies in slot 23 formed in the stand. When there is sufficient weft present for continued weaving the actuator lever 21 will be free to descend in slot 23, but when insufficient weft is present a controller pin 24 will be under the outer end of the actuator lever 21 and as the block 20 descends rod 22 will be given a downward movement to initiate replenishment. The matter thus far described is of common construction and may be as set forth in the aforesaid patent, the only difference being that controller pin 24 is somewhat different from that shown in the aforesaid patent.

In carrying out my invention I provide a bracket 30 to which is bolted a stand 31 having a horizontal slot 32 to receive a bolt 33 which passes through a vertical slot 34 formed in support 35. The upper part of the support is flattened as at 36 to form the

lower portion of a detector housing the upper part of which is provided by a cap 37. The support is provided with a boss 38 and is surrounded for the most part by an upstanding flange 39. Said flange is broken away at the rear right portion to define a shoulder 41 and there is projecting inwardly from the left hand side of the flange a lug 42 which defines a notch 43.

10 The detector which I employ is formed of a single piece of wire D bent at the rear portion thereof and having teeth 44 cut therein, the forwardly extending portion of the wire being curved as indicated in Fig. 1 and normally lying in contact with shoulder 41. Said wire is provided with a bent portion 45 and a straight portion extending to the left as indicated at 46. The extreme forward end of the wire is formed as a pivot indicated at 47 so proportioned as to be received in notch 43. The distance between the right hand portion of the bend 45 and the left end of the detector is slightly less than the distance between the inside side walls of the flange 39, the purpose of this construction being to prevent undue lateral movement of the detector. The forward portion of the wire is provided with a crimp 48 which receives the forward end of a coil spring 49 the rear end of which is received by a projection 50 cast on the support. The normal function of the spring 49 is to hold the pivot portion 47 in the notch 43 and the curved rearwardly extending part of the detector against shoulder 41 thus positioning said detector for proper engagement with the surface to be detected.

In carrying my invention into further effect I provide a withdrawing wire W having a right hand leg 60 provided with an open hook 61 which engages both sides of that portion of the detector D located between the end 47 and crimp 48. The portion 36 is provided with a wall or shoulder 62 which guides the lower end of the hook to prevent movement to the left as viewed in Fig. 1. The cap 37 prevents upward displacement of the leg 60 and the latter is therefore held against improper vertical and lateral movement to the left.

The other leg 63 of the withdrawing device terminates in the controller 24, passing into a portion of stand 19 so that the controller 24 normally lies under actuator 21. The withdrawing wire is formed as one piece and the forward portion thereof is looped as at 64, the sides of the loop being in substantial alignment and being so placed as to be engaged by one of the legs 17 of the trans-

60 ferrer lever.

Under normal conditions the parts will be in the position indicated in full lines in Fig. 1 and as the shuttle and bobbin advance the teeth 44 will be embedded in the yarn and

65 the detector D will move forwardly from the

full line position indicated in Fig. 1 without angular movement. The said detector moves the wires W forwardly to withdraw the controller 24 from under actuator lever 21 so that the latter is free to descend without interruption. When insufficient yarn for continued weaving is present, however, the teeth 44 will slide along the empty bobbin to the dot and dash line position indicated in Fig. 1, the detector D under these conditions moving around the notch 43 as a pivot. The hook 61 is so near the notch that the angular movement of the detector produces no appreciable effect on the controller 24 and the latter therefore remains under the actuator lever 21 to interrupt the downward movement of the latter and initiate replenishment.

On a subsequent beat of the loom when the exhausted shuttle again arrives under the magazine the transerrer arm will be moved downwardly by mechanism not shown and one of the legs 17 will engage the wire W and move the same forwardly to the dotted line position indicated in Fig. 2, this motion of the transerrer moving the detector D to the dotted line position indicated in Fig. 1 to clear the path of the incoming bobbin and also moving the controller pin 24 from under the actuator lever 21 so that the latter may descend without repeating the indication.

It occasionally occurs that the detector must be adjusted longitudinally with respect to the bobbin and shuttle, this adjustment being permitted by the slot 32 but inasmuch as stand 19 remains fixed it is necessary to provide some adjustment to vary the distance between the legs 60 and 63. This can be done by spreading the legs apart or drawing them closer together as the case may be, the loop 64 either contracting or being enlarged according to which adjustment is made. As indicated in Fig. 6 the legs have been separated with a consequent contraction of the loop 64. Whatever the distance between the withdrawing and controller ends of the wire W, there will always be a portion which lies in the path and is under control of some part of the transerrer mechanism. For this reason the controller and detector will always be moved to inoperative position on a transferring beat independent of the lateral position of the support 35.

From the foregoing it will be seen that I have provided a very simple device for withdrawing a side slip weft detector on transferring beats of the loom, this device serving also as a controller for the actuator lever. It will further be seen that the controller is normally in operative position with respect to the actuator lever and that angular movement of the detector produces a negligible movement on the part of the controller so that the latter is in operative position on

indicating beats of the loom. It will furthermore be seen that by means of the surplus material afforded by the loop 64 I am enabled to vary the distance between the 5 legs 60 and 63 when lateral adjustments of the detector is necessary and that for all such adjustments the device is under control of the transferring mechanism.

Having thus described my invention it will 10 be apparent that changes and modifications may be made therein by those skilled in the art without departing from the spirit and scope of the invention, and I do not wish to be limited to the details herein disclosed 15 but what I claim is:

1. In a loom weft detector having a yarn 20 engaging element and a support, the element supported entirely by the support and being movable forwardly on the support 25 when engaging a bobbin having sufficient weft and moving angularly about a portion of the support as a center along a bobbin having insufficient weft, an actuator, 30 transferring mechanism, and a member operatively connected to and moving with the element when the latter has a forward non-indicating movement, said member having a portion normally in the path of the actuator, said portion being withdrawn when 35 the element moves when in contact with sufficient weft and remaining in the path of the actuator when the element is in contact with insufficient weft, the transferring means engaging the member at the time of 40 transfer to withdraw the detector from the path of the incoming bobbin and said portion from the path of the actuator.

2. In a loom weft detector having a yarn 45 engaging element and a support, the element supported entirely by the support and being movable forwardly on the support when engaging a bobbin having sufficient weft and moving angularly about a portion of the support as a center along a bobbin 50 having insufficient weft, an actuator, and a controller for the actuator moving with the element when the latter has a forward non-indicating movement, said controller operatively connected to the element at a point 55 closely adjacent the center about which the element moves when in contact with an insufficient supply of weft.

3. In a loom weft detector having a yarn 60 engaging element and a support, the element supported entirely by the support and being movable forwardly on the support when engaging a bobbin having sufficient weft and moving angularly about a portion of the support as a center along a bobbin having 65 insufficient weft, resilient means to hold the element in normal bobbin engaging position, an actuator to effect a change in the operation of the loom, and a member common to the element and actuator moving with the element when the latter has a for-

ward non-indicating movement and remaining in the path of the detector when the element moves angularly when in contact with an insufficient supply of weft, said yielding means being operative to hold the member 70 normally in the path of the actuator.

4. In a loom weft detector having a yarn 75 engaging element and a support, the element being movable forwardly on the support when engaging a bobbin having sufficient weft and moving angularly about a portion of the support as a center along a bobbin having insufficient weft, resilient means to hold the element in normal bobbin 80 engaging position, an actuator to effect a change in the operation of the loom, and a member common to the element and actuator and lying in the path of the latter when the element moves angularly when in contact with an insufficient supply of weft, said yielding means being operative to hold the member 85 normally in the path of the actuator, said member being formed with a contractable and expandable part, whereby the distance between the actuator and element 90 engaging portions thereof may be varied.

5. In a loom weft detector having a yarn 95 engaging element and a support, the element being movable forwardly on the support when engaging a bobbin having sufficient weft and moving angularly about a portion of the support as a center along a bobbin having insufficient weft, resilient means to hold the element in normal bobbin 100 engaging position, an actuator to effect a change in the operation of the loom, and a member common to the element and actuator and lying in the path of the latter when the element moves angularly when in contact with an insufficient supply of weft, said yielding means being operative to hold the member 105 normally in the path of the actuator, said member being formed as a wire having a loop formed therein which may be contracted or expanded to increase or diminish the distance between the actuator and element engaging portions of said member.

6. In a loom weft detector having a yarn 110 engaging element and a support, the element supported entirely by the support and being movable forwardly on the support when engaging a bobbin having sufficient weft and moving angularly about a portion of the support as a center along a bobbin having insufficient weft, an actuator to effect a change 115 in the operation of the loom, a transferring, and a member acting both as a controller means for the actuator and a withdrawing means for the element when said member is engaged by the transferring, said member moving with the element when the latter has a forward non-indicating movement and remaining under the actuator when insufficient weft for continued weaving is in contact 120 125 130

with the detector to effect a change in the operation of the loom.

- 7: In a loom weft detector having a yarn engaging element and a support, the element formed of a single piece of wire supported entirely by the support and being movable forwardly on the support when engaging a bobbin having sufficient weft and moving angularly about a portion of the support 10 as a center along a bobbin having insufficient weft, an actuator to effect a change in the loom, and a member common to the actuator and element and comprising a single piece of wire operatively connected to the 15 element at a point closely adjacent the por-

tion of the support about which the element moves as a center, said member moving forwardly when the element is in contact with sufficient weft so that said member is out of operative engagement with the actuator and said member remaining substantially at rest because of its location with respect to the point about which the element turns when the latter is in engagement with an insufficient supply of weft, the member 25 in the latter named position being operatively disposed with respect to the actuator.

In testimony whereof I have hereunto affixed my signature.

HAROLD L. BLANCHARD.
